OPERATING TABLE

Runar Alopaeus, Helsingfors, Finland

Application September 28, 1937, Serial No. 166,180
In Finland October 2, 1936

5 Claims. (Cl. 311—7)

The present invention relates to an improved operating table, the table-top of which consists of several parts, which are adjustable relative one another as well as adjustable all together sideways and in vertical direction. The invention relates especially to the system by which this adjustment is carried out.

The following is a full, clear, and exact description of the invention. Reference is made to 10 the accompanying drawings in which,

Fig. 1 shows the table with its adjusting system seen from below, the view being a section on the line 1—1 of Fig. 2.

Fig. 2 illustrates same seen from one side,

Figs. 3—6 show in diagrammatic manner side-views of the table with the adjusting system in different positions.

Fig. 7 is a detail side elevation later again referred to.

20 It is necessary that operating tables be adjustable not only as to height and inclination, but the table-top must also be arranged so as to make it possible to place the body of the patient in those different positions, which are necessary to carry out the desired operation. A further requirement is, that said table-top parts must be adjustable easily and conveniently.

It is of course already known in the art to divide the top of an operating table into different parts which are adjustable relatively to one another. The adjustment device for these table-top parts has, however, been an object for numerous experiments, nevertheless a simple and conveniently operated adjusting system has not been obtained.

It is known in the art to provide a system adapted to adjust the different parts of the table-top independently of one another by means of screws, hydraulic pumps etc. It has further been proposed to regulate the position of the table-top parts by means of a three armed support, which is fixed to two of the table-top parts and further to pivoted operating rods under the head end of the table. This embodiment has however also proved not quite satisfactory, because the three-armed support piece is complicated to arrange and fix correctly to the table-top parts and further this construction requires so much power for the adjustment operation that it has proved to be necessary to arrange strong springs in the system, which however complicate the system. Finally such a three-armed support piece requires considerable space below the table and thus obstructs the knees of the surgeon at such

operations he has to carry out in sitting position keeping his legs under the table.

The operating table according to the present invention removes said disadvantages and is constructed as follows:

The table-top of the operating table is, as has heretofore been the practice, divided into a number of parts 1, 2, 3, 4 and 5 connected together by means of pivots 6, 7, 8 and 9. The table rests on a central pillar 10, which is provided with a known hydraulic arrangement for the lifting and lowering of the table-top. The joint between the table-top parts 3 and 4 is provided with a slide locking arrangement of suitable kind, which when unlocked, permits pivoting of the parts at the joint, but as long as it is kept locked, prevents the parts 3 and 4 from moving relative each other. Such a locking mechanism is shown in Figs. 1, 2 and 7, by reference to which it will be seen that a rod 23 is pivoted at 21 to a block 10 on the under side of table section 3 and passes through a member 25 pivoted at 22 to the under side of section 4, a set screw 24 being provided to hold slide rod 23 in its adjusted positions in member 25.

The adjustment system consists of two operating rods 11 extending longitudinally under the table. At one end the rods are provided with suitable handles, and at the other end they are pivotably arranged between flanges 12, situated at that end of the table-top part 2, which is directed towards the central carrying pillar 10 of the table. The flanges 12 have such a length that the connecting point 19 between said flanges 12 and the rods 11 lies somewhat lower than the bearing 13 on the pillar 10 around which the operating table i. e. its longitudinal axis is turned in the vertical plan.

The rods 11 are further rigidly connected to two slidable locking devices 14 and 15, of which the one, 14 is slidably and lockably connected to a guide rod 16, which at 18 is pivotably connected to the central carrying pillar 10 at a point 18 situated lower than the pivoted bearing 19 of the rods 11 in the flanges 12, and the other 15, in the same manner slidably and lockably on the guide rod 17, arranged on the underside of the table-top part 4 and parallel to same in the longitudinal direction of the table.

By means of the rods 11, i. e. by lifting or lowering them by their handles and by simultaneously locking one or both of the slide blocks to their sleeves, the table-top parts can be given any position necessary for the operation in question.

The adjustment of the table-top parts into dif-

ferent positions is in the following statement described with reference to the Figures 3-6, where in order to render the idea of the invention more obvious only the parts 2, 3 and 4 of the table-top 5 are shown. Said table-top parts carry respectively the patient's seat, stomach and chest part and his shoulder part. The table-top parts 1 and 5, which carry the patient's legs and head, thus relatively light parts, may be connected with the 10 abutting table-top part in any suitable way and are of no importance for the invention.

The position of the table-top shown in Fig. 2 is assumed as starting position for every movement. In Fig. 2 the lower slide block 14 is visible.

When it is desired to swing all table-top parts together simultaneously, i. e. as one single rigid table-top e. g. in order to obtain a position according to Fig. 3, the slide block 15 is locked (indicated by the dot 15^x in Fig. 3) on its guide rod 17, so as not to permit any relative movement between these two members, while on the other hand the locking device of the slide block 14 is loosened, so as to permit this to slide along the 25 guide rod 16. By this arrangement the table-top parts 2, 3 and 4 together form a plate, which at both ends is connected to a stiff rod, in consequence whereof the parts cannot change their mutual position, but are forced as one single 30 plate to follow every movement of the rods 11. If the handles of the rods 11 thus are pressed downwards, a position according to Fig. 3 is obtained. During the swinging movement the slide block 14 slides freely forwards and backwards 35 along the guide rod 16.

If the position shown in Figures 4 and 5 is desired, the locking mechanism of the slide block 15 is unlocked, while the slide-block 14 is locked (indicated by the dots 14^x in Figs. 4 and 5) on its 40 guide rod 16, as to fix the distance between the slide-block 14 and the bearing 18 on the carrying pillar 19 of the rod 16. If the rods 11 now are lifted or lowered, the rod 16, the slide-block 14 and the point 20 will swing around the bearing point 18. The swinging radius of the movement of the slide-block is shorter than is the swinging radius for its movement around the bearings of the rods 11 in the flanges 12, i. e. the point 19. Thus by the swinging movement a stress arises 50 in the longitudinal direction of the rods between the connecting point on the rods 11 of the block 14 and their bearings in the flanges 12 i. e. between the points 19 and 20. The bearing point 19 is movable together with the flanges 12 and 55 the table-top part 2, around the link 7 whilst the point 20 is fixed. The aforementioned stress in the longitudinal direction of the rods 11 pushes or pulls the bearing 14 in the one or the other direction accordingly as the rods 11 are lifted or 60 lowered.

If the rods are lifted, the point 19, and together with it the flange 12, will be pushed to the left, see Figure 4, and the position illustrated in said Fig. 4 is obtained. By lowering the rods 11 a 65 pulling stress will arise in them, with a result opposite to that described by the aforementioned operation i. e. the point 19 will be pulled toward the carrying pillar 19 and a position according to Fig. 5 obtained.

70 It should be observed, especially when adjusting the table into the position shown in Fig. 4, that the plate 2, due to the fact that the plate is operated at its inner end by means of the downwardly projecting flanges 12, will be lowered in 75 a position always parallel to its starting posi-

tion. Herein lies a considerable difference especially against the known system, which works with the above mentioned three-armed support piece.

If the surgeon wishes to place the patient into the so called "gall-position", and adjust the table accordingly, see Fig. 6, the slide-block 14 as well as the slide-block 15 are fastened (indicated by the dots 14^x-15^x in Fig. 6), whereas the screw 24 in the member 25 is loosened. If now the rods 11 are lifted, the pressure between the points 19 and 20 will bend the table-top at the pivot 7 as well as at the pivot 8.

The slide blocks 14 and 15 may be locked to their respective guide rods 16 and 17 in any known way, as for example by set screws 14^x and 15^x respectively.

Having now fully described my invention, I claim:

1. In an operating table, a pedestal, a top composed of at least three articulated plates arranged end to end and constructed to support the patient's seat, back and shoulders respectively, the middle one of which is pivotally mounted on said pedestal, an adjusting mechanism common to said three plates and including an operating member pivoted at one end to a second of said three plates and extending beneath the other plates, a rod fixed to the third plate, a second rod pivoted to said pedestal and lying adjacent said first mentioned rod, slide members connected to said operating member at a fixed point and slidably mounted respectively on said rods, and means to hold at will said slide members from sliding on their respective rods. 30

2. An operating table the table top of which is supported on a central pillar and divided into a plurality of table-top parts angularly adjustable relative to one another, comprising longitudinally arranged rods secured pivotally to flanges carried by that end of the table-top part for the patient's seat directed towards the central part of the table-top and to two mutually combined slide blocks arranged at the side of the central pillar remote from said flanges, one of 45 said slide blocks being adapted to slide and lock on a guide rod pivoted to the central support pillar and arranged below the first-mentioned rod and the other slide block being adapted to slide and lock on a guide rod arranged rigidly on the 50 part of the table-top for the patient's shoulders and above the other guide rods.

3. An operating table as claimed in claim 2 having longitudinally extending operating rods, secured to the table-top plate for the patient's seat at a point situated lower than the main supporting bearings of the table on its central pillar. 55

4. In an operating table, a pillar, a table top comprising at least three articulated members 60 connected together end to end, means to pivotally mount the intermediate one of said members on said pillar, at least one guide rod mounted longitudinally under and on a second one of said three members, a slide block on said guide rod, means 65 to lock said slide block to said rod at any position desired, a rod pivoted to said pillar, a second slide block on said last named rod, at least one operating rod pivotally connected to the third of said members, means pivotally connecting both 70 of said slide blocks to said operating rod on a common pivotal axis, and means for locking said second slide block to its rod at any desired position.

5. In an operating table, a pillar, a table top 75

comprising at least three articulated members connected together end to end, means to pivotally mount the intermediate one of said members on said pillar, at least one guide rod mounted longitudinally under and on a second one of said three members, a slide block on said guide rod, means to lock said slide block to said rod at any position desired, a rod pivoted to said pillar, a second slide block on said last named rod, at least one operating rod pivotally connected to the third of

said members, means pivotally connecting both of said slide blocks to said operating rod on a common pivotal axis, means for locking said second slide block to its rod at any desired position, and adjustable means connecting said intermediate and said second table-top members together to hold the same against articulation when desired.
